UNITED STATES PATENT OFFICE

159,224

BUILDING

George Pafume, Forest Park, Ill.

Application August 17, 1948, Serial No. 148,147

Term of patent 3½ years

(Cl. D13—1)

To all whom it may concern:

Be it known that I, George Pafume, a citizen of the United States, residing at Forest Park, in the county of Cook and State of Illinois, have invented a new, original, and ornamental Design for a Building, of which the following is a specification, reference being had to the accompanying drawing, forming part thereof.

Figure 1 is a perspective view of a building, showing my new design.

Fig. 2 is a front elevational view; and

Fig. 3 is an end elevational view on a reduced scale.

The rear of the building presents the same appearance as the front thereof.

I claim:

The ornamental design for a building, as shown and described.

GEORGE PAFUME.
